COMBINATION FLATIRON AND CLOTHES DAMPENER

Patrick J. Fitzgerald, Torrington, Conn., assignor to The Fitzgerald Manufacturing Company, Torrington, Conn., a corporation of Connecticut

Application August 29, 1939, Serial No. 292,415

4 Claims. (Cl. 38—78)

This invention has to do with a combination flatiron and clothes dampener, and is concerned with a novel arrangement of the clothes dampening mechanism on the iron structure.

The present day conventional flatiron has now assumed a more or less standard form and generally comprises an iron body having a pointed nose and a substantially square heel, and which iron body carries front and rear brackets that in turn carry a handle. If the iron is of the electrically heated type, a control switch is usually included in the iron body as between the handle carrying brackets, and suitable provision is made for connecting an electric cord thereto, such as by spaced connecting posts.

From the very use to which the clothes dampening mechanism is to be put, it is desirable that the same include a spray nozzle that is positioned above the nose of the iron and from the structural characteristics and mode of usage of the iron, it is desirable that the water reservoir of the dampening mechanism be located at the heel of the iron. Obviously, it is essential that there be a suitable conduit connecting the water reservoir with the spray nozzle, and it is also obviously necessary to include, at a suitable location, a pump that may be operated as occasion demands to eject a spray from the spray nozzle.

With the foregoing conditions in mind, and also recognizing that the flatiron is normally grasped by one hand of the operator, this invention has in view, as an important objective, the provision of a combination flatiron and clothes dampener in which one of the brackets which ordinarily supports the handle is replaced by a pump and which pump is operated by downward pressure at an appropriate point on the iron handle.

In view of the fact that the usual ironing operations require a forward movement of the iron, that is, in the direction of the nose, the invention has, as a further object, the provision of a combination of a flatiron and clothes dampener, in which the rear handle supporting bracket is replaced by a pump with the handle of the iron constituting the operating means for the pump.

Still more in detail the invention has in view the provision of an arrangement in which the handle is pivotally mounted at the front bracket and is also pivotally connected at the rear end to the pump mechanism. The pump mechanism is in turn mounted in such a way as to accommodate swinging movement of the handle about its hinged mounting at the front bracket.

Another object of the invention is the pro-

5 vision of a combination flatiron and clothes dampener of the character above noted and in which the pump is of the cylinder and piston type with the cylinder being pivotally mounted on the iron body while the piston is pivotally connected to the handle.

10 While it is convenient for an operator to depress the handle to effect operation of the pump, it is not quite so convenient for the operator to impart an upward movement to the handle. Accordingly, a further object of the invention is the provision in a combination flatiron and clothes dampener of the character above noted, of spring means normally maintaining the handle, and with the handle the piston of the pump, in an upraised position.

15 A still further more detailed object of the invention is the provision of an arrangement in which the spring means is associated with the hinged mounting of the handle on the front bracket.

20 The arrangement of clothes dampening mechanism on a flatiron, in accordance with the above noted objectives, and particularly the mounting of the pump in the manner aforesaid presents certain conditions which must be accommodated in order to provide a practical assembly. In the first place, the cylinder of the pump which is located at the rear of the handle must be connected to the reservoir and in view of the movement of the pump cylinder, which is a necessary incident to operation of the pump, the connections must be such to accommodate this movement.

25 35 Furthermore, the pump cylinder at the rear must be connected with the spray nozzle at the front and the connections must be such as not to interfere with the operation of the control switch for the iron.

40 It is also desirable that the connections be not easily damaged, as by accidental striking against objects, and this is also true of the spray nozzle which is positioned over the nose of the iron.

45 Accordingly, the invention has in view, as a further object, the provision of a combination flatiron and clothes dampener of the character above noted and in which a flexible conduit is employed as the means for connecting the reservoir to the pump cylinder and also as a means 50 for connecting the pump cylinder to the spray nozzle at the front. This flexible conduit is properly shaped to circumvent the control switch and not interfere with the operation thereof.

Various other more detailed objects and advantages of the invention such as arise in con-

nection with effecting a practical embodiment of the above noted thoughts will in part become apparent and in part be hereinafter stated as the description of the invention proceeds.

The invention, therefore, comprises the combination of a flatiron including an iron body having a pointed nose and a substantially square heel and which iron body carries a front handle supporting bracket to which a handle is hingedly connected. The handle is connected at the rear with the iron body by a pump of the cylinder and piston type, this cylinder being hingedly connected to the iron body with the piston connected to the pump handle. Spring means are provided for normally maintaining the handle in an upraised position and the spring means is preferably associated with the hinged mounting at the front. A water reservoir is carried by the iron body at the heel thereof and this reservoir is connected with the cylinder of the pump by a flexible conduit. A spray nozzle is positioned over the nose of the iron body and this spray nozzle is also connected with the cylinder of the pump by a flexible conduit.

For a full and more complete understanding of the invention, reference may be had to the following description and accompanying drawings, wherein:

Figure 1 is a side view partly in section and partly in elevation of a combination flatiron and clothes dampener, embodying the principles of this invention.

Figure 2 is a plan view of the mechanism shown in Figure 1 with the handle of the iron removed.

Figure 3 is an enlarged view developing the reservoir and iron handle with the associated pump mechanism in a contracted relationship, the flexible conduit between the reservoir and pump being broken away.

Figure 3a is a section through the reservoir and connections leading thereto.

Figure 4 is an enlarged detail view with the pump cylinder from the rear shown in the manner from which the flexible conduits are connected thereto, and

Figure 5 is an enlarged detail sectional view through the spray nozzle.

Referring now to the drawings and first more particularly to Figures 1 and 2, a flatiron made in accordance with the present day design is shown as comprising an iron body 10 as formed with a pointed nose 11 and a substantially square heel 12. This iron body 10 has an ironing surface designated 13 and a top surface identified by the reference character 14.

While the present invention is applicable to irons which are heated from some source exteriorly of the iron, the invention is designed primarily for use with so-called electric irons. When the iron is of the electric type the iron body houses the electrical heating elements (not illustrated) in a manner well-known in this art, and a control switch for turning the iron on or off, as occasion demands, is shown at 15 as mounted on the top surface 14.

Suitable provision is also made for connecting the heating elements of the irons with a suitable source of current, such means taking the form of spaced connecting posts 16 that are positioned above the heel 12.

Referring now more particularly to Figures 1 and 3, a front handle supporting bracket is designated 17 and is formed with a foot 18 that is anchored to the top surface 14 in the iron body 10 by the headed screw fastening element shown

at 19. The upper end of the bracket 17 is curled over to provide a passageway for the hinged pintle and which passageway is designated 20. As shown more particularly in Figure 2, the curled over structure which defines the passageway 20 takes the form of spaced curled over tongues 21.

Referring now again to Figures 1 and 3, a handle is designated 22 and is shown as formed at its forward end with a recess 23 having a flat bottom 24 to which is anchored a hinge part 25, the anchorage being effected by a screw fastening member 26 that passes through an opening in the part 25 and is embedded in the handle 22.

It will be noted that the hinge part 25 is formed with a curled tongue 27 that is received between the curled over tongues 21 of the bracket 17 and a hinge pintle 28 passes through the aligned passages of the curled over tongues to effect the hinge connection. It is important to note that a leaf spring 29 has a part 30 interposed between the hinge part 25 and the bottom 24 of the recess 23, the screw fastening element 26 providing a good clamping effect. This spring 29 has another part 30a that bears against the bracket 17. The spring 29 exerts a tendency normally maintaining the handle 22 in its uppermost position; however, the handle may be depressed against the influence of the spring.

At the rear the handle 22 is also formed with a recess 31 having a bottom wall 32 and a top wall 33. A bracket in the form of an angle bar 34 is fitted in the recess 31 with a part 35 engaging the bottom wall 32 and another part 36 engaging the top wall 33. A screw fastening element 37 passes through an opening in the part 35 and is embedded in the handle to securely clamp the angle bar 34 in position in the recess 31.

Depending downwardly from the top wall 33 are a pair of spaced ears 38, each of which is formed with an opening, through which opening passes a pivot pin 39. A pump plunger 40 of cylindrical formation is formed at its upper end with a tongue 41 that is received between the ears 38 and which tongue 41 is formed with an opening through which the pivot pin 39 also passes.

Secured to the upper face 14 of the iron body 10, as by a head and screw fastening element shown at 42, is a foot hinge piece 43, the rear edge of which is inclined slightly upward and turned back to define spaced curled over tongues 44, these curled over tongues 44 defining a passage for a hinge pintle 45.

A pump cylinder 46 has a closed bottom 47 from which projects downwardly a tongue 48 that is received between the curled over tongues 44. This tongue 48 is formed with an opening through which the hinge pintle 45 passes. A piston assembly is shown as mounted for reciprocating movement in the bore of the cylinder 46 and is identified at 49. This piston assembly 49 is carried at the end of the plunger 40. A closure member 50 is screwed into the upper open end of the cylinder 46 and is provided with a bore 51 which slidably receives the plunger 40. This cylinder 46 is formed on opposite sides with openings 52 which are designed for connection with the flexible conduits in a manner to be hereinafter described.

It is evident that upon depression of the handle 22 the plunger 40 is moved downwardly to cause a corresponding movement on the part of the piston 49. However, upon release of the

handle, the spring 29 is effective to raise the same and with it the plunger 40 and piston 49.

A spray nozzle is shown in detail in Figure 5 and is referred to generally by the reference character 53. The spray nozzle 53 houses a 5 check valve 85 which cooperates with the free end of a flexible conduit 54 that is connected to the spray nozzle. The flexible conduit 54 passes through a bracket 55 that is carried by the fastening element 19 between the head of this fastening element and the foot 18 of the bracket 11. As shown in Figure 2, this flexible conduit 54 extends rearwardly out around the control switch 15 and is connected to one of the openings 52 in 10 the pump cylinder 46 by a coupling represented 15 at 56.

Referring now more particularly to Figure 1, a reservoir-carrying bracket is referred to in its entirety by the reference character 57 and is shown as comprising a pair of spaced wings 58 20 (see Figure 2), which are positioned on each side of the connecting posts 16 and have an anchorage in the iron body 10. The reservoir-carrying bracket 57 also includes a bottom 59 that is bent back on itself with the bent back portion designated 60 and which portion 60 is anchored in the iron body above the heel 12. At each side of the bottom 59 is an ear 61.

A water reservoir is identified in its entirety by the reference character 62 and is shown as 30 being carried by the bracket 51 being positioned between the ears 61. This water reservoir 62 comprises a bottom wall 63 which rests on the bottom 59 and a top 64 which is connected to the bottom by the inclined front and rear walls 65 and 66, respectively. The top 64 is formed with an air vent designated 67, which air vent is of a well-known construction. The water reservoir also includes a pair of end walls 68.

Adjacent the lower end the rear wall 66 is thickened, as shown at 69, and the thicker portion is provided with a threaded opening 70. A valve-carrying sleeve 71 is exteriorly threaded and screwed into the threaded opening 70. A nut 72 is threaded over the sleeve 71 and bears against the washer 13 which in turn engages the thickened portion 69 of the reservoir wall 66. This nut 72 serves to securely lock the sleeve 71 in position.

A flexible conduit 74 has one end secured to the pump cylinder 46 by the coupling represented at 75, while the other end of this flexible conduit 74 carries a coupling member 76, which coupling member is formed with a groove 77 and a conical tip 78. A thimble 79 is threaded on the upper end of the sleeve 71 and carries a flange 80 that is received in the groove 77. The conical tip 78 is inserted in the bore of the sleeve 71 so that upon tightening of the thimble 79, a good waterproof connection between the flexible conduit 74 and the sleeve 71 is provided. The sleeve 71 is formed with a bore which terminates at its inner end with a valve seat 81, which valve seat has an opening that communicates with the interior of the reservoir 62.

A valve member in the form of a ball member 82 is seated in the valve seat 81 and is normally maintained seated by a spring 83 that is fitted in the bore of the sleeve 71 and bears against appropriate backing provided therefor, such as indicated at 84. One of the end walls 68 is provided with an opening that is normally closed by the closure shown at 86 in Figure 1. The closure 86 may be removed when it is desired to refill the reservoir 62.

The manner in which the above described mechanism functions in actual usage is believed to be obvious, but may be briefly described by noting that the spray nozzle 53 is normally and conveniently positioned over the nose 11, while the reservoir 62 carries an appropriate supply of water. As has been pointed out the spring 29 normally maintains the handle 22 in an upraised position.

During ordinary ironing operations the operator presses forwardly on the iron rather than downwardly and the water-dampening mechanism is not effective. However, when it is desired to dampen a certain portion of clothes, the operator presses down on the rear end of the handle 22. This causes a downward movement of the plunger 40 and piston 49 so that water in the bore of the cylinder 46 is forced through the openings 52 in one wall thereof into the flexible conduit 54 and past the valve 85 out through the spray nozzle 53 in the form of a spray, any return of water in the bore of the cylinder 46 being prevented by the ball valve 82 which is maintained seated on its seat 81 by the spring 83 and the pressure of the water.

When the operator releases the handle 82 the spring 29 moves the same upwardly. As the piston 49 is moved upwardly in a corresponding manner, the check valve 85 at the upper end of the conduit 54 closes, shutting off the atmosphere. Thus, a partial vacuum is created, the ball valve 82 is unseated from its seat 81, opening communication with the interior of the reservoir 62, and water is drawn from the reservoir 35 into the bore of the cylinder 46, again putting the pump into condition, in which downward pressure of the handles causes ejection of the spray.

While a preferred specific embodiment of the 40 invention is hereinbefore set forth, it is to be clearly understood that I am not to be limited to the exact construction illustrated and described, because various modifications of these details may be provided in putting the invention 45 into practice, within the purview of the appended claims.

I claim:

1. In combination, a flatiron comprising an iron body having a nose and a heel, a front handle supporting bracket upstanding from the iron body, a handle pivoted to said bracket and extending towards said heel, a clothes dampening mechanism comprising a pump interposed between the free end of said handle and the iron body, a water reservoir at the heel, fluid connections between said reservoir and pump, a spray nozzle at the nose, and fluid connections between said spray nozzle and pump.

2. In combination, a flatiron comprising an iron body having a nose and a heel, a front handle supporting bracket and a handle pivotally secured to said bracket, clothes dampening mechanism comprising a pump, said pump including a plunger pivotally connected at one end to said handle, a cylinder pivotally mounted on said iron body, a water reservoir at the heel of the iron, a flexible conduit connecting said water reservoir with the cylinder of said pump, a spray nozzle at the nose, and a flexible conduit connecting the cylinder of the said pump with said spray nozzle.

3. In combination, a flatiron comprising an iron body, a handle supporting bracket upstanding from the iron body, a handle pivotally carried by said bracket, a pump interposed between

said handle and said iron body and operable incident to movement of the handle with respect to the iron body, spring means associated with the pivotal mounting of the handle normally maintaining said handle in an upraised position, a spray nozzle carried by the iron body, connections between said spray nozzle and said pump, a water reservoir, and connections between the water reservoir and said pump.

4. In combination, a flatiron comprising an iron body having a nose and a heel, a front handle supporting bracket upstanding from the iron

body, a handle pivoted to said bracket and extending towards said heel, spring means normally maintaining said handle in an upraised position, a clothes dampening mechanism comprising a pump interposed between the free end of said handle and the iron body, a water reservoir at the heel, a flexible conduit connecting said water reservoir and said pump, a spray nozzle at the nose, and a flexible conduit connecting said pump and spray nozzle.

PATRICK J. FITZGERALD.
